UNITED STATES PATENT OFFICE

159,132

DRESS

Oscar A. Berman, New York, N. Y.

Application October 11, 1949, Serial No. 5,422

Term of patent 14 years

(Cl. D3—26)

To all whom it may concern:

Be it known that I, Oscar A. Berman, a citizen of the United States, residing at 25 East 77th Street, in the county of New York and State of New York, have invented a new, original, and ornamental Design for a Dress, of which the following is a specification, reference being had to the accompanying drawing, forming part thereof:

My design is characterized by the specific arrangement of pin tucked squares on the blouse, skirt, and sleeves, as shown.

I claim:

The ornamental design for a dress, as shown and described.

OSCAR A. BERMAN.
